UNITED STATES PATENT OFFICE.

DAVID McNAIR, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,759, dated May 4, 1880.

Application filed April 7, 1880. Term of patent 3½ years.

To all whom it may concern:

Be it known that I, DAVID McNAIR, of Boston, in the county of Suffolk and State of Massachusetts, have invented a new and original 5 Design for Carpets, of which the following is a specification.

My present design is illustrated in the accompanying photograph, forming part of this specification, and to which reference is made 10 in the following description.

It consists in the flat conventional floriated patterns A and A', repeated at regular intervals, as shown, and interspersed with smaller figures of similar character and irregular outline, B and B', the whole connected and arranged with general uniformity of purpose 15 upon a plain ground.

I claim—

The design for a carpet herein shown and described, consisting of the flat conventional floriated patterns A A', repeated at regular intervals and interspersed with smaller irregular figures of similar character, B B', the whole connected upon a plain ground, as set forth.

In testimony whereof I have signed my name 25 to this specification, in the presence of two subscribing witnesses, this 1st day of April, A. D. 1880.

DAVID McNAIR.
